UNITED STATES PATENT OFFICE.

PAUL G. GARBER, OF PHILADELPHIA, PENNSYLVANIA.

DESIGN FOR A PIANO-CASE.

SPECIFICATION forming part of Design No. 32,516, dated April 10, 1900.

Application filed March 15, 1900. Serial No. 8,844. Term of patent 7 years.

To all whom it may concern:

Be it known that I, PAUL G. GARBER, a citizen of the United States, residing at No. 1129 Arch street, in the city and county of Philadelphia, in the State of Pennsylvania, have invented a new and original Design for a Piano-Case, of which the following is a specification, reference being had to the accompanying drawing, forming part hereof, which is a front elevation of a piano-case, showing my new design.

My design has particular relation to that portion of the front of an upright-piano case which is above the keyboard; and the leading or material feature of my design consists in a series of comparatively-small lozenge-shaped panels placed with their long axes horizontally and arranged in horizontal and perpendicular supplementary rows, occupying that portion of the piano-case to which I have just referred. These panels are formed by a series of inclined bars or tongues intersecting at the angles of the lozenges and di-

viding that portion of the front of a piano-case into a considerable number of lozenge-shaped panels having their long axes placed horizontally—say five horizontal rows and seven vertical rows—as shown in the drawing.

My design therefore consists in the upright-piano case, the upper portion of which is provided with the series of lozenge-shaped panels, the long axes of which are placed horizontally, as described.

Having thus described my invention, what I claim as new, and desire to secure by Letters Patent, is—

The design for a piano-case as herein shown and described.

In testimony whereof I have signed my name to this specification in the presence of two subscribing witnesses.

PAUL G. GARBER.
